(57) CLAIM

The ornamental design for a baby bodysuit, as shown and described.

DESCRIPTION

FIG. 1 is a perspective view of the baby bodysuit, showing the new design;

FIG. 2 is a front elevational view of the baby bodysuit thereof;

FIG. 3 is a rear elevational view of the baby bodysuit thereof;

FIG. 4 is a left side elevational view of the baby bodysuit thereof;

FIG. 5 is a right side elevational view of the baby bodysuit thereof;

FIG. 6 is a top plan view of the baby bodysuit thereof;

FIG. 7 is a bottom plan view of the baby bodysuit thereof; and,

FIG. 8 is an alternate position view of the baby bodysuit thereof.

The evenly dashed broken adjacent to the shaded surface lines depict portions of the baby bodysuit that form no part of the claim. The dash dot lines depict the boundary of the claim and form no part thereof. The smaller evenly dashed lines that cross claimed surfaces depict stitching that forms no part of the claim.

1 Claim, 6 Drawing Sheets
